US00D501249S

(12) **United States Design Patent** (10) Patent No.: **US D501,249 S**
Millan (45) Date of Patent: **** Jan. 25, 2005**

(54) **COMPONENT FOR EVAPORATORS OF ACTIVE SUBSTANCES**

D481,787 S * 11/2003 Millan D23/366
D491,256 S * 6/2004 Fellows et al. D23/366

(75) Inventor: **Jordi Basagañas Millan**, Barcelona (ES)

* cited by examiner

(73) Assignee: **DBK Espana, S.A.**, Barcelona (ES)

Primary Examiner—Lisa Lichtenstein

(**) Term: **14 Years**

(74) Attorney, Agent, or Firm—Michael Best & Friedrich LLP

(21) Appl. No.: **29/185,095**

(57) **CLAIM**

(22) Filed: **Jun. 23, 2003**

The ornamental design for a component for evaporators of active substances, as shown.

(30) **Foreign Application Priority Data**

DESCRIPTION

Dec. 23, 2002 (ES) 155853

FIG. 1 is a first perspective view of the instant invention;

(51) **LOC (7) Cl.** **23-04**

FIG. 2 is a second perspective view thereof;

(52) **U.S. Cl.** **D23/366**

FIG. 3 is a rear elevational view thereof;

(58) **Field of Search** D23/366-369;

FIG. 4 is a top plan view thereof;

422/120, 122-124; 239/34-60, 211; 261/DIG. 65

FIG. 5 is a front elevational view thereof;

(56) **References Cited**

FIG. 6 is a right side elevational view thereof;

U.S. PATENT DOCUMENTS

FIG. 7 is a left side elevational view thereof; and,

D480,792 S * 10/2003 Millan D23/366

FIG. 8 is a bottom plan view thereof.
